UNITED STATES PATENT OFFICE

ROLLAND BUSLAFF, OF WAUKESHA, AND HERMAN L. ENGELS, OF MARSHFIELD, WISCONSIN, ASSIGNORS TO UNIVERSAL MILKING MACHINE COMPANY, OF WAUKESHA, WISCONSIN

VACUUM PUMP AND TANK

Application filed January 12, 1929. Serial No. 332,114.

This invention relates to a vacuum tank and pump, particularly intended for use with milking machines.

Objects of this invention are to provide a combined pump and vacuum tank which are formed as a unit and which are so constructed and inter-related that the entire structure is not top heavy, nor is it very large, and in which adequate bracing for the pump and motor is secured while permitting the free removal of the pump and motor for repair, inspection or other purposes, with a minimum of parts that need be handled.

Further objects are to provide a device in which the vacuum tank itself is so made that a compartment is formed which constitutes the crank case and oil-carrying portion of the pump, in which the pump is securely braced with reference to the tank, in which the pump is so constructed that the cylinder and the operating parts thereof may be readily removed from the tank and also cooperate with the tank to prevent splashing or leaking of the oil outwardly therefrom, and which prevents the entrance of moisture or dirt into the crank case.

Further objects are to provide a device in which the vacuum tank serves in its normal capacity as a vacuum tank and also serves as a base for the pump and motor, and in addition provides a pocket at one end which serves as a crank case, without in any way requiring a heavier construction for the tank and without requiring any elaborate or difficult operations in the production of the tank.

Further objects are to provide a novel form of pump in which the valves are very simple and are carried by a valve unit which is freely removable to thereby afford easy access to the valves and in which the valves are so made that a relatively large area of opening is afforded without increasing the weight of the valves.

An embodiment of the invention is shown in the accompanying drawings, in which:

Figure 1 is a side elevation of the apparatus with parts broken away.

Figure 2 is a sectional view on the line 2—2 of Figure 4.

Figure 3 is an enlarged sectional view

showing the pump and a portion of the vacuum tank.

Figure 4 is a plan view of the pump structure with parts in section.

Figure 5 is a sectional view on the line 5—5 of Figure 4.

Referring to the drawings, it will be seen that a rectangular vacuum tank 1 is provided and is equipped with a plurality of bosses 2, welded to the inner side of the tank and threaded to receive the attaching bolts of the electric motor 3. This motor is mounted on the top of the vacuum tank, as shown in Figure 1, and is provided with a driving pulley 4. The vacuum tank is provided with a drain plug 5 and with an inlet pipe 6 adapted to lead to the milking machine, or the apparatus with which the device is used.

The vacuum tank is provided with a small, upwardly opening compartment 7 which is sealed in an air-tight manner, by welding or other means, from the interior of the tank. The compartment 7 serves as a crank case for a pump, and the pump is formed preferably with a pair of cylinders 8 provided with a flanged outwardly extending flared portion or bottom 9, such portion being provided with a downwardly extending flange 10 adapted to fit into the compartment 7, and with an outwardly extending flange 11 adapted to rest upon the upper portion of the tank, as shown in Figure 3.

The base portion of the cylinders of the pump are provided with apertured lugs 12 located within the tank and adapted to receive bolts 13 extending through the walls of the tank, as may be seen from Figures 1 and 3.

One side of the compartment 7 is provided with a slot 14 to receive the crank shaft 15 of the pump, such crank shaft being carried by a pair of bearing members 16 on opposite sides of the compartment 7, such bearing members being formed integrally with the cylinder block. One of the bearing members closes the slot when the pump is slipped into place.

From the construction thus far given, it is apparent that stresses are not imparted to the tank by rotating the pump shaft, but instead, all of the stresses are borne by the inte-

gral pump structure itself. The pump shaft is provided with a pair of cranks connected by links 16' with pistons 17. The cylinders are provided with an integral, laterally extending valve head 18 (see Figure 4) within which relatively wide and narrow passageways or ducts 19 are formed, such passageways leading into the cylinders, as shown in Figure 4.

- 10 Further, each passageway leads to a cylindrical aperture 20 which communicates with a relatively smaller cylindrical aperture 21, so as to form a shoulder, such smaller aperture in turn opening into an inlet chamber 22. 15 A valve chest or valve cap 23 is secured by means of screws 24 to the top of the valve head, as shown most clearly in Figure 2. As may be seen from Figure 5, this cap, or valve chest 23, covers both valves and is provided 20 with an outlet aperture 25.

A valve-carrying unit is provided for each cylinder. The units are of identically the same construction and one only, therefore, need be described. The unit consists of a 25 member 26 which fits within the cavity of opening 20 and rests upon the shoulder formed at the bottom of such opening. It is held in place by means of the screw 27. This member is provided with a reduced central portion 28 which slidably carries a valve disc 29, such valve disc being in reality an annular washer-like member, and freely 30 slidable upon the reduced portion 28. It closes the apertures through the member 26 when in seated position, as shown in Figure 3. Above the member 26 a second member 30 is 35 positioned and fits within the cylindrical aperture 20. This member is provided with an outwardly extending flange 31 which rests upon the top of the valve head 18.

The member 30 is provided with a reduced projection 32, and is held in place by an overhanging member 33, spaced from the body of the member 30 and contacting with the upper 45 end of the reduced portion 32. This overhanging member 33 projects over each of the cylindrical openings 20 for the cylinders, as may be seen from Figure 5, and is held in place by means of a single screw 34 (see Figure 4). It is provided with a plurality of ribs 35 to prevent sticking of the outlet, 50 annular valve 36, such valve being similar to the valve 29 and freely slidable upon the reduced portion 32.

55 The member 30, similar to the member 26, is provided with a plurality of outlet apertures closed by the ring-like valve 36.

It is thus apparent that the outer member 33 may be readily removed, together with the 60 valve-carrying unit, to permit inspection, repair or cleaning of the valves.

It is apparent that there can be no leaking, as the suction pipe 37 (see Figure 3) opens directly into the inlet or suction cavity 22 of the pump. Consequently, no gasket is need-

ed for the valve cap 23, as this cap merely forms the discharge chamber.

In addition to these features, it is to be noted that the pipe 37, which is threaded into the valve head, is joined by means of a flexible hose 38, with a short pipe 39 welded to the vacuum tank, thus providing a simple, inexpensive connection which is readily attached or dismantled and which eliminates vibration upon the welded connection of the suction pipe 39 with the vacuum tank. Also, the flexible coupling 38 avoids the necessity of close, accurate fittings and alignment of parts.

It will be seen further that the valve construction is such that the valves, as stated, are simple, sure in their seating action, and may be readily removed for inspection or renewal. Further than this, by providing a crank case for the pump formed as a portion of the vacuum tank itself, the pump may be set down lower with reference to the tank, thereby avoiding a top-heavy construction.

The pump shaft 15 is provided with a pulley 40 connected by means of a belt 41 with the pulley 4 of the motor. Obviously, a silent chain drive or other drive could be substituted for the one disclosed herein.

It will therefore be seen that a very compact construction has been provided, which has a combined pump and vacuum tank as well as a driving motor.

Although this invention has been described in considerable detail, such description is intended as illustrative rather than limiting, as the invention may be variously embodied and as the scope of such invention is to be determined as claimed.

We claim:

1. In a combined vacuum tank and pump, the combination of a tank having a closed vacuum compartment and an open compartment; a cylinder block provided with an inlet portion and having a flanged base seated within said open compartment; a pair of bearings rigid with the base of the pump and extending downwardly into said open compartment; a crank shaft for said pump carried by said bearings and located within said open compartment; means for driving said crank shaft; means for detachably securing the pump to said tank; and means connecting the inlet portion of said pump with said vacuum compartment.

2. In a combined vacuum pump and vacuum tank, the combination of a tank having a vacuum compartment, and having an inset open top compartment, said last mentioned compartment serving as a crank case; a pump comprising a cylinder block having a base flange and fitting within the upper end of the open compartment, and having an outwardly projecting flange resting upon said tank; means for detachably securing said base in

place; a crank shaft carried by said base and positioned within said open compartment; said pump having a laterally extending valve head on said cylinder block provided with an inlet portion and having a valve cap provided with an outlet portion; a pipe joining the inlet portion of said pump with said tank; an electric motor mounted upon the upper side of said tank, said tank having means for attaching said motor in place; said crank shaft having a pulley located exteriorly of said tank and belted to said motor.

3. In a combined vacuum tank and pump, the combination of a tank having a closed vacuum compartment and an open compartment, a cylinder block provided with an inlet portion, a base forming a closure for the open compartment, a pair of bearings rigid with the base of the pump and extending downwardly into said open compartment, a crank shaft for said pump carried by said bearings and located within said open compartment, means for driving said crank shaft, means for detachably securing the pump to said tank, and means connecting the inlet portion of said pump with said vacuum compartment.

4. In a combined vacuum tank and pump, the combination of a tank having an enclosed vacuum compartment and an open compartment, a cylinder block provided with an inlet portion, a base mounted upon said tank above said open compartment, a pair of bearings rigid with the base of the pump and extending downwardly into said open compartment, a crank shaft for said pump carried by said bearings and located within said open compartment, means for driving said crank shaft, means for detachably securing said pump to said tank, means connecting the inlet portion of said pump with said vacuum compartment.

In testimony that we claim the foregoing we have hereunto set our hands at Waukesha, 45 in the county of Waukesha and State of Wisconsin.

HERMAN L. ENGELS.
ROLLAND BUSLAFF.
